PATENTED
SEP 28 1869

John T. Webster

United States Patent Office.

JOHN T. WEBSTER, OF NEW YORK, N. Y., ASSIGNOR TO PAGE, WILDER & CO., OF HALLOWELL, MAINE.

Design No. 3,684, dated September 28, 1869.

DESIGN FOR FLOOR OIL-CLOTH.

The Schedule referred to in these Letters Patent and making part of the same.

To all whom it may concern:

Be it known that I, JOHN T. WEBSTER, of the city of New York, in the county of New York, and State of New York, have originated and designed a new Pattern for Floor Oil-Cloths or other fabrics, of which the following is a full, clear, and exact description, reference being had to the accompanying drawings, making part of this specification.

The drawings, painted in colors on what is known as design-paper, represent a complete design for floor oil-cloths, or other printed or woven fabrics.

This design, when repeated, consists of small chintz groups, on light-colored panels of rectangular form,

overlying a frame-work enclosing hexagonal or octagonal and diamond-shaped centres.

The drawings represent more fully, clearly, and exactly, than any written description can do, the nature and extent of my invention.

What I claim as my invention, and desire to secure by Letters Patent, is—

The design or pattern for floor oil-cloths or other fabrics, herein set forth.

JOHN T. WEBSTER.

Witnesses:

THOMAS JEFFERY,
WM. H. BRODHEAD.
